United States Patent Office.

JOHN WEBSTER COCHRAN, OF NEW YORK, N. Y.

Letters Patent No. 75,626, dated March 17, 1868.

IMPROVEMENT IN FIXED-AMMUNITION HOLDERS FOR CARTRIDGE-BOXES.

The Schedule referred to in these Letters Patent and making part of the same.

TO ALL WHOM IT MAY CONCERN:

Be it known that I, JOHN WEBSTER COCHRAN, of the city, county, and State of New York, have invented a new and useful Improvement in Frames for Cartridge-Boxes; and I do hereby declare that the following is a full, clear, and exact description of the same, reference being had to the accompanying drawings, making a portion of this specification, in which—

Figure 1 is a vertical transverse section of a frame of a cartridge-box made according to my invention.

Figure 2 is an internal view of one of the sides of the same.

Figure 3 is an internal view of the opposite side thereof.

Similar letters of reference indicate corresponding parts in all the figures.

This invention is designed for carrying the so-called metallic cartridges, and its object is to provide a frame for cartridge-boxes, in which the cartridges will be securely retained in place without danger of being brought in contact or jammed against each other, and which will also permit the convenient insertion of the cartridges therein, or removal of the same therefrom.

The invention consists in two recessed plates, one or both of which are formed of India rubber or other like elastic material, so combined with a suitable supporting-frame as to hold or suspend the cartridges at their ends and independently of each other, thereby effectually securing the desired result.

To enable others to understand the nature and construction of my invention, I will proceed to describe it with reference to the drawings.

A represents a rectangular frame, designed, when in use, to be fitted or placed within the cartridge-box in the ordinary or in any suitable manner, and which may be of wood or other appropriate material. The two sides of the box are shown, respectively, at A* B*, and the side, A*, is formed, preferably, with holes, a, as indicated in fig. 1, the said holes a being arranged in longitudinal series, one series above the other. Attached in any suitable way upon the internal surface of the side, A*, is a plate, B, which is recessed at its inner side, or, rather, provided with cup-shaped portions, b, which extend back into the holes a in the side, A*, and which receive the pointed or bullet-ends of the cartridges, as hereinafter fully set forth. Secured in like manner to the inner surface of the other side, B*, of the frame A, and formed, preferably, of the same or like material, is an elastic plate, C, in the internal surface of which are provided circular recesses, c, formed with flat bottoms, as shown in fig. 1, and corresponding in diameter to the diameters of the flanged or butt-ends, which they are designed to receive, of the cartridges, the depth of the said recesses c being equal to or slightly greater than the thickness of flanges of the cartridges. The recesses c are placed immediately opposite the cavities or recesses of the cup-shaped portions, b, at the other side, A*, of the frame.

In order to place or insert the cartridges in the frame, each of the cartridges, of which one is shown at D in fig. 1, is taken singly, and its pointed or bullet-end is fitted and pressed into the recess, or cavity of one of the cup-shaped portions b of the plate B with such a degree of force as to cause such portion to yield sufficiently to permit the butt-end of the cartridge to be pressed downward to the opposite recess, c, in the plate C, whereupon the elasticity of the aforesaid cup-shaped portion b forces the butt or flanged end of the cartridge into the recess c, just mentioned, so that, the pointed end of the cartridge being held in the recess of such portion b, while its butt-end is held in the recess c, as shown in fig. 1, it is firmly retained in place. The cartridges may be thus arranged in positions parallel with each other, with a slight space between them, and are, by this means, prevented from coming forcibly in contact with each other, and from jamming or lying loose in the frame, the cartridges being, furthermore, so situated that they may be very conveniently grasped with the fingers, and removed from the frame.

If desired, the plate C, instead of being made of elastic material, as described, may be of wood or other hard substance, and, if thought proper, may be formed in one piece with the side, B*, of the frame, a slightly-increased degree of elasticity being required in the plate B when the plate C is thus made of hard material. Furthermore, it is possible, by making the plate B of sufficient thickness, to dispense with the holes a in the plate A*, in which case the convex form of the backs of the cup-shaped portions b, hereinbefore described, will be dispensed with, the purpose of such portions b being served by cup-shaped recesses formed in the inner

surface of the plate A*, and receiving the pointed ends of the cartridges in the same manner as hereinbefore described.

What I claim as my invention, and desire to secure by Letters Patent, is—

The plates A* B*, recessed as described, in combination with the frame A, substantially as and for the purpose specified.

J. W. COCHRAN.
